DESIGN FOR A SHOE

Otto Newman, New York, N. Y., assignor to Triumph Shoe Co., Inc., New York, N. Y., a corporation of New York

Application November 21, 1938, Serial No. 81,262

Term of patent 3½ years

To all whom it may concern:

Be it known that I, Otto Newman, a citizen of the United States, residing at New York city, in the county of New York and State of New York, have invented a new, original, and ornamental Design for a Shoe, of which the following is a specification, reference being had to the accompanying drawing, forming part thereof.

In the drawing

Fig. 1 is a perspective view of a shoe showing my new design;

Fig. 2 is a front view thereof.

I claim:

The ornamental design for a shoe, as shown.

OTTO NEWMAN.
